Andrew Smelser Jr.

UNITED STATES PATENT OFFICE

SAMUEL HOFFMAN, OF SOUTH ORANGE, NEW JERSEY, ASSIGNOR TO J. CHEIN & COMPANY, OF HARRISON, NEW JERSEY, A CORPORATION OF NEW YORK

TOY DRUM

Application filed September 12, 1931. Serial No. 562,475.

My invention relates to improvements in toy drums.

An object of my invention is to provide a novel and useful device of the character specified. A further object of my invention is to provide certain new and useful details of construction in a toy drum. Other objects and advantages will appear by the following specification.

I accomplish these and other objects by my invention a preferred embodiment of which is illustrated in the drawing in which

Fig. 1 is a perspective view of a toy drum and

Fig. 2 is a section on the line 2—2 in Fig. 1.

Similar characters of reference refer to similar parts throughout the several views.

My improved drum comprises a cylindrical band 1 preferably of sheet metal having inwardly bent channels 2 and 3 forming interiorly disposed beads or shoulders 4 and 5 adjacent the respective ends of the cylinder 1.

Two counterpart metal drum heads 6 and 7 preferably provided with peripheral bent over flanges 8 and 9 respectively and of such size as to enter the cylinder 1 and 2 be seated on the shoulders 4 and 5 respectively are inserted in the respective ends of the cylinder 1 and pressed down upon the said shoulders 4 and 5.

A plurality of tongues 10, 11, 12 are cut out of the marginal edge sections of the cylinder 1 above the heads 6 and 7 and pressed over on the said heads to bind and hold the same in position on said shoulders.

The cut out portions 10', 11' and 12' respectively formed by cutting out the said tongues 10, 11 and 12 respectively are adapted to be used as eyelets for the binding cord 13.

The margins 14 and 15 of the cylinder 1 are preferably rolled over to provide a suitable finish to the exposed edges.

The exterior surface of the device may be painted, lithographed or otherwise decorated as desired.

The device is preferably constructed of sheet metal in all its parts, and may be provided, if desired, with a cord 13 laced through the eyelets 10', 11' and 12' or the

cord 13 may be omitted. One of the said heads 6 and 7 may be omitted, if desired.

Having thus described my invention, what I claim is:

1. A toy drum comprising in combination a cylinder, shoulders inwardly disposed adjacent the ends of said cylinder, heads each having a peripheral flange set at a right angle to the head with its marginal edge seated on one of said shoulders within the marginal edge of the cylinder, tongues cut out of the said marginal edge section of the cylinder and pressed down upon said heads, eyelets formed by said cut out tongue apertures in the marginal edge sections of said cylinder and a cord laced in said eyelets. 65

2. A toy drum comprising in combination a cylinder, shoulders inwardly disposed adjacent the ends of said cylinder, heads each having a peripheral flange set at a right angle to the head with its marginal edge seated on one of said shoulders within the marginal edge of the cylinder, tongues cut out of the said marginal edge section of the cylinder and pressed down upon said heads, eyelets formed by said cut out tongue apertures in the marginal edge sections of said cylinder, the said cylinder having rolled edges spaced from said heads. 75

Signed at New York in the county of New York and State of New York this eighth day of September A. D. 1931. 80

SAMUEL HOFFMAN.
